UNITED STATES PATENT OFFICE.

RANDOLPH CROMPTON, OF WORCESTER, MASSACHUSETTS.

STOPPING MECHANISM FOR TEXTILE APPARATUS.

1,142,751.

Specification of Letters Patent.

Patented June 8, 1915.

Application filed July 19, 1913. Serial No. 779,972.

To all whom it may concern:

Be it known that I, RANDOLPH CROMPTON, a citizen of the United States, and a resident of Worcester, in the county of Worcester and State of Massachusetts, have invented an Improvement in Stopping Mechanism for Textile Apparatus, of which the following description, in connection with the accompanying drawings, is a specification, like characters on the drawings representing like parts.

This invention relates to stopping mechanism for textile apparatus, and particularly for looms.

15 In order that the principle of the invention may be readily understood, I have disclosed a single embodiment thereof in the accompanying drawings, wherein—

Figure 1 is a vertical section of a loom 20 from front to rear and having my invention applied thereto; Fig. 2 is a front elevation, with parts broken away, of the construction shown in Fig. 1; Fig. 3 is a detail on a larger scale than Fig. 2 of a portion of the heddle 25 frame guiding means and related parts; Fig. 4 is an end elevation of the construction shown in Fig. 3; Fig. 5 is a vertical section on the line 5—5 of Fig. 4; Fig. 6 is a view 30 partially in plan and partially in horizontal section, of the heddle frames and guiding means therefor, parts being broken away; Fig. 7 is a detail in front elevation showing a portion of the electrical connections of the 35 stopping mechanism; Fig. 8 is a vertical section on the line 8—8 of Fig. 7; Fig. 9 is a view in vertical section and somewhat dia- 40 grammatic representing four warp threads, the shed being closed; Fig. 9^a is a view in front elevation, of a portion of one of the heddle devices; Fig. 10 is a view similar to Fig. 9, but representing the shed open; Fig. 45 11 is a view similar to Fig. 10, but representing the change occurring upon breakage or fault of one of the warp threads; Fig. 12 is a detail in side elevation of a portion of the 50 shipper mechanism; Fig. 13 is a similar view in rear elevation and representing the lay in section; Fig. 14 is a view partially in transverse section and partially in plan of 55 the construction shown in Figs. 12 and 13; and Fig. 15 is a view, partially in elevation and partially in section, upon the line 15—15 of Fig. 13.

Looms have long been provided with warp 55 stop motions which have been placed in the

harness so as to form a part thereof or have been placed in the rear of the harness, but in almost all cases it has heretofore been necessary to rely upon the action of gravity, and therefore to use parts of substantial weight 60 in the nature of drop bars or the like.

In all commercial stop motions for looms known to me employing heddle stops, the heddle has acted through gravity to initiate the stoppage of the loom. This has necessitated the use of metallic or like heddles inflexible or non-collapsible in the direction of their length, although highly flexible laterally. In practice, the metallic drop heddles have given fair satisfaction upon certain 70 kinds of fabrics, but upon certain classes of warps, these heddles have been found to be impracticable, as they result in the roughening and chafing of the yarn and the breaking of its tender strands. In an attempt to overcome this objection, and particularly in the weaving of cloth involved in the use of finer and more delicate warps, the drops have been located behind the harness, and therefore in a position where they do 75 not receive that amount of vertical recipro- 80 cation incident to the shedding action of the warps, or in certain cases they have been so positioned that they receive no movement due to the shedding action alone. The objections to this latter class of stop devices are, however, serious for there is involved a large complement or supply for each loom at least as many as the number of 85 ends used. This involved, with many classes 90 of drop devices, the drawing of the warp ends through the drops as well as through the harness, thus largely increasing the labor incident to the preparation of the warp for the loom. While drop devices positioned 95 back of the harness do less injury to the warp ends in the weaving operation than do the metallic drop heddles, nevertheless the former class of drop devices does seriously injure certain classes of goods and especially 100 silk goods. The so-called "cotton harness," by which term I include harnesses made of textile material such, for example, as cotton or twine or material that is collapsible in the direction of its length, is universally ac- 105 knowledged to be best adapted for use upon fine work. I have succeeded in utilizing the so-called "cotton harness" as a warp stop device, and thus I retain all the advantages 110 of such class of harness and in addition

5 avoid the necessity of drawing the warp ends through a harness and also through drop devices. I thereby effect the shedding of the warp with the least possible chafing thereof, and at the same time there is necessitated no more labor in the drawing in of the warp than in the ordinary type of looms having no warp stop motions.

10 Metallic drop devices are open to certain serious objections, such as the rusting and the electrifying thereof. The latter phenomenon, which is of frequent occurrence in loom practice, results in the holding of the drop of a faulty warp end in place, so that 15 the warp fault is not indicated.

15 In the preferred embodiment of my invention, I employ stop devices, which are of the type of so-called "cotton harness," to which I have referred, and which do not rely or 20 depend upon the action of gravity to effect the stoppage of the loom in the event of warp fault. The stopping action is thus rendered more certain because no electrification of drops can occur, and because there 25 is less crowding of parts. Moreover, in that embodiment of the invention herein disclosed, I provide a positive initiation of the stopping action as contrasted with one which is initiated through the action of gravity. 30 Furthermore in that embodiment of the invention herein disclosed, the broken or faulty warp end is elevated above the plane of the warps or above the upper plane of the shed of the warps, instead of being depressed as heretofore, and thus the broken end may be readily seen and more readily repaired.

35 Other advantages of my invention will be readily apparent from the description of 40 that single embodiment thereof which I have herein disclosed.

45 Referring more particularly to the drawings, I have therein represented a conventional type of loom having side frames 1 and 2, breast beam 3, a lay 4 operated in any suitable manner and a let off 5. These parts may be of any suitable or desired construction, and other parts of the loom commonly employed are omitted for clearness of 50 illustration.

55 My invention may be employed with any desired number of heddle frames or supports. I have herein illustrated but two heddle frames, but it is clearly to be understood that my invention is not limited thereto, although I shall describe my invention and the functioning of the various parts thereof with reference to the employment of but two heddle frames.

60 Referring more particularly to Figs. 2 to 6 inclusive, I have therein indicated two heddle frames 6, 7, the former having upper and lower cross members 8, 9, and the latter having upper and lower cross members 10, 11. The said heddle frames are reciprocated

6 by any suitable shedding mechanism (not shown), and to which they are connected by suitable strips 12. Preferably the heddle frames are connected to the floor or to a suitable base by means of spiral springs 13, 14, connected to the said frames by hooks 15.

70 For the sake of clearness, I have shown but a single heddle in Fig. 2, but have diagrammatically indicated the same in Figs. 1, 9, 10 and 11. The number of heddles is 75 proportional to the number of warp ends, and they are preferably formed of some suitable textile material, such as cotton, though I desire it to be clearly understood that for the accomplishment of certain advantages and objects of my invention, I may employ heddles which are formed partially or wholly of some suitable metal, such for example as wire. One of the advantages of 80 my invention is that the broken warp end is 85 lifted incident to the stoppage of the loom, and this result may be effected by the use of a metallic heddle, but preferably I employ heddles of textile material, because of the many advantages incident to their use, and 90 certain of which I have above set forth.

95 In Figs. 1, 2, 9, 10 and 11, I have indicated two heddle devices 16, 17, each of which is duplex in that it receives two warp ends. Each heddle device is represented as 100 composed of a continuous, twisted strand, piece or band of textile material, such as cotton, cord or twine, and is passed about the upper member 8 or 10 and the lower member 9 or 11 of its heddle frame in such 105 a manner that it can travel longitudinally; that is, in the direction of its own length and in either direction. Each duplex heddle may be regarded, and particularly when viewed in side elevation, as in Figs. 9, 10 and 11, as composed of two members lettered 110 respectively A and B and C and D, although preferably, as previously stated, each heddle device is continuous and uninterrupted. Each of the members A, B, C and D is provided with a suitable eye or 115 warp receiving formation 18, and through the several eyes pass the four warp ends respectively letters a, b, c and d. Although each heddle device may be made in any suitable manner, I preferably construct the same of a continuous strand, piece or band of textile material, such as twine, which is of universal flexibility and is soft so as not to act harshly upon the warp ends. 120

125 Viewing each heddle device in front or rear elevation, reference being made to Figs. 2 and 9^a, it will be observed that each member C or D is composed of two strand portions e, f (extending from the other member) and passing down in parallelism to the point g where they are crossed or formed into a half knot and separated to form a loop or eye h, being again brought together and recrossing at i to complete the loop or 130

eye and being then continued downwardly in two parallel strands as indicated at *j*, *k*.

In reality, the entire device is composed of a single twine or piece, which is uninterrupted and without knot or crossing at the point of support of the upper heddle member, and at the point of support of the lower heddle member the parts of the two members of the double heddle device 5 may be knotted together and continued beyond the knot as hereinafter described. It will thus be observed that the eye of each heddle is composed in the disclosed embodiment of the invention of the same material 10 as the other portions of the heddle and that no knots, but on the contrary merely crossed strands or half knots, are presented to the warp end of the heddle eye. In order to prevent any expansion or stretching of the 15 heddle when the unbroken warp end imparts longitudinal movement thereto, I suitably size or otherwise treat the heddle. In the manner described or in any other suitable manner, I prevent any longitudinal expansion, which, if it occurred to any suitable extent, would prevent initiation of 20 loom stoppage. It will be observed that the eye or thread receiving formation of each heddle member is elongated, and preferably it is suitably varnished for the 25 passage of the thread. It will furthermore be observed that each eye is substantially centrally positioned with respect to upper and lower cross members of the heddle frame 30 to which it pertains. Each heddle device to which I hereinafter refer as the heddle is provided with means whereby the movement initiated upon the breaking or fault in a warp end is transferred to the stopping mechanism proper. Preferably for 35 this purpose, I provide each heddle with an extension or loop 20, which is also preferably of textile material and may be integral or in one piece with the main portion of 40 the heddle, this result being effected by knotting or tying the heddle at 21 below the lower cross bar 9 or 11 of the heddle frame, as previously indicated, but with sufficient slackness to permit the lengthwise travel 45 of the heddles about said cross members 8 and 9. The loops 20 of all the heddles receive therein a tube, rod or bar 22 constituting a portion of the stopping mechanism, and to which I shall hereinafter refer in 50 detail. This tube is preferably metallic, inasmuch as, in the preferred embodiment of my invention, I employ electrical connections to effect the stoppage of the loom.

I desire it to be understood that instead 55 of employing loops 19, 20, I may utilize any other suitable operating connections between the heddles and the stop rod 22 and that other stopping motion transmitting devices may be substituted for the rod, tube 60 or bar 22. The length of the loops 19, 20

is such that in the lifting of the heddles in the shedding action, the bar 22 is not disturbed as is evident from a comparison of Figs. 9 and 10. When, however, warp fault occurs, such as warp breakage and as indicated at *c* in Fig. 11, then the unbroken warp end *d* of the companion warp ends *c*, *d* received by the duplex heddle device, shown at *D* in Fig. 11, immediately imparts longitudinal movement to the heddle device 70 in the direction of the arrow in Fig. 11, because the said warp end is, in the shedding operation, drawn from a true horizontal plane. The consequence of the downward movement of the member *D* of the duplex 75 heddle is the simultaneous upward movement of the member *C* of the same heddle, carrying with it the broken or faulty end *c* into the elevated position shown in Fig. 11. Thus the broken or faulty warp end is lifted 80 above the plane of the shed in which it occurs and the loop 20 is drawn into the position shown in Fig. 11, thereby lifting the bar 22 from the dotted line position shown in said figure to the full line position, thus 85 operating the stopping instrumentalities and preferably by closing a circuit.

I have thus far assumed that the warp end that is broken is one in the upper plane of the shed. It is evident that if the warp 90 fault or breakage occurs when the broken or faulty warp is in the lower plane of the shed, the described movement of the heddle upon its supporting members 8, 9 occurs when the heddle frame thereof is lifted in 95 the shedding operation. In other words, if a warp end breaks when in the lower plane of the shed, such warp end, as soon as it is moved into the upper plane of the shed, is instantly lifted above said plane of said 100 shed, as indicated in Fig. 11.

The relative arrangement of the threads passing through the heddles of the various frames depends upon the number of such frames. In that simple form of the invention herein illustrated and having reference to the threads as they are introduced into the loom in sheet form, the first and third threads are passed through the eyes 18 of one of the heddle devices and the second and fourth threads are passed through the eyes of the other heddle device. The warp ends are distributed through a greater number of heddles in an obvious manner, not herein necessary more fully to particularize. It is 110 evident that such breakage of warp ends as will prevent the instant initiation of loom stoppage is remote, and that this remoteness increases with the increase in the number of heddle frames. For example, and considering merely the use of two heddle frames, if the two warp ends which pass through the eyes of the two members of a single heddle both break and both break precisely simultaneously, then initiation of loom stoppage 115 120 125 130

is not effected, but if both threads of said heddle break, and the breakage of one precedes the breakage of the other by a small fraction of time, such for example as one third of a second in looms running at the rate of one hundred and eighty picks a minute, it is evident that loom stoppage is effected. Thus, it is only in the remote contingency that of all the warp ends in the loom the two threads that break are the two threads of a single heddle and such breakage is absolutely simultaneous, is there failure to initiate loom stoppage. I have demonstrated the fact, and particularly with looms employing a greater number of harnesses, that the chance of failure to initiate loom stoppage is almost infinitesimal. Any suitable means may be employed to effect loom stoppage upon the initiation thereof in the manner described. In the disclosed embodiment of the invention, I have represented electrically controlled means operatively connected with the stopping mechanism proper, to which I shall hereinafter refer broadly as the shipper mechanism

The harness may be guided in any suitable manner. Preferably I employ means which will support them with capacity for yielding movement toward either side frame of the loom and toward the front or back thereof, the construction being such in the selected embodiment of my invention that the bar 22 partakes of such movements of the harness, so that the relative position of the harness and the said bar is not disturbed or substantially disturbed excepting when warp fault occurs. It will thus be observed that the bar 22 and the set of heddle frames with which the bar co-operates are "self contained", all being kept in the same horizontal relation during the operation of the loom. Thus the heddles are free to move toward either side frame of the loom, or toward the front or rear thereof, and in the event of such movement the bar 22 moves therewith but without any displacement until warp fault occurs.

I preferably provide upright metal strips 23, 24 pivoted at 25 in suitable socket pieces 26 secured to the floor, thus permitting said strips to rock toward and from the front or rear of the loom. Said strips are quite highly flexible, and therefore permit lateral movement of the heddle frames. As shown most clearly in Figs. 2 to 6 inclusive, each of the strips 23, 24 has secured to its upper end in any suitable manner guide blocks 27, 28, having open-ended slots, as shown in Fig. 6, for the reception of the heddle frames 6 and 7. The said heddle frames are reciprocated through the usual instrumentalities in said guide blocks 27, 28, and the latter are held in proper relation to each other in any suitable manner, but preferably by readily detachable devices, such as cotter

pins 29 inserted through corresponding members 30 of said guide blocks. By removing said cotter pins, the strips 23, 24 may be separated, thus freeing the heddle frames 6, 7 therefrom. In order to support the stop bar 22, I preferably provide suitable terminal boxes represented at 31 in the several figures. These boxes are composed of some suitable insulating material, and are recessed as indicated at 32 to receive the ends of the bar 22, which, if desired, may have the reduced ends 33.

The recess 32 is elongated as represented in Figs. 7 and 8 to permit the cross bar 22 to be elevated upon the occurrence of warp fault as heretofore described. I preferably provide means to effect adjustment of the boxes 31 upon the strips 23, 24, the adjustment being herein represented as a vertical one. For that purpose I have provided each box 31 with a strip 34 secured by screws 35 and having therein a vertical series of holes or sockets 36, any one of which is adapted to be entered by a pin 37 upon a plate spring 38 resting flatwise against the strip 23 or 24 and secured thereby by screws 39. The strip 34 is preferably extended upward, resting flatwise against the upper portion of the strip 23 or 24 and being held thereagainst by a suitable wire or clip 34', as represented in Figs. 2 to 5 inclusive, into convenient position to be grasped by one hand of the operator for vertical adjustment when the pin 37 is withdrawn from one of the holes 36 to be inserted in another hole of said series.

Each of the boxes 31 receives an end 40-40 of a wire 41 constituting part of an electric circuit and preferably each recess 32 is lined or provided with a metallic piece 42 of general inverted V-shape as represented in Fig. 7. The said lining piece 42 is connected to the ends 40 of the wire 41 so as together to constitute terminals with which the ends of the rod 22 may contact when lifted upon the occurrence of warp fault.

The circuit of which the wire 41 forms a part is provided with a battery 43 and wire 44 extending to a magnet 45 represented most clearly in Figs. 12 and 14 and which when energized attracts the armature 46 pivoted at 47 upon a suitable support. The stop bar 22 is connected by a wire 48 to the magnet so that upon the lifting of the bar 22 the circuit is closed and the armature 46 attracted so as to operate the shipper mechanism through any suitable connections.

The loom may be stopped through the action of the described instrumentalities in any suitable manner, but preferably by a shipper device 49 of usual construction. The shipper is held in the usual notch and when released therefrom shifts the belt through the instrumentality of the shipper rod 50 in a manner not necessary more fully

to describe. In order that upon the closing of the circuit and the movement of the armature 46 the shipper may be operated, I have herein provided the lay 4 of the loom 5 with a suitable bracket 52 having pivoted thereon a dog 53 having a hooked end 54 which is suitably downwardly pressed by a plate spring 55. The dog 53 moves to and fro with the lay in a fixed path which is at 10 one side of the upturned end 56 of a bar 57. When, however, the armature is attracted upon the closing of the circuit, the said upturned end 56 is moved in the direction of the arrow in Fig. 14 to bring it into the 15 path of movement of the dog 53 so that the movement of the lay in the direction of the arrow in Fig. 13 moves said upturned end with it through the engagement of the dog 53. The said upturned end 56 is formed 20 upon a bar 57 having a hooked end 57' to engage and move the shipper, and is also provided with longitudinal slots 58 as shown in Fig. 13, through which pass screws 59, thereby holding said bar flatwise against the 25 armature with capacity for limited sliding movement thereon. A coil spring 60 connected to one of the screws 59 and to a hook 61 upon the bar 57 normally holds the said bar in the position indicated in Fig. 13, 30 but upon engagement of the dog 53 with the upturned end 56 the said bar 57 yields. The described lost motion connection of the bar 57 with the armature 46 is provided in this embodiment of the invention because the 35 movement of the lay is greater in extent than the movement necessary to pull the shipper from its notch.

The support for the magnet 45 is provided with a suitable extension or bracket 40 62 bent at an angle as represented at 63 in Fig. 14 so as to lie below and substantially parallel with a right-angled extension 64 of the bar 57. The said extension 64 is provided with a down-turned or hooked end 65 45 as represented in Fig. 15, and when the armature is attracted the said hooked end 65 takes over and engages the end 66 of the extension 63, thus holding the armature against the magnet and holding the upturned 50 end 56 in the path of the dog 53 so that even though the circuit be immediately broken by the lowering of the heddle frame containing the faulty warp thread, loom stoppage will be effected as described.

55 Immediately upon the energization of the armature 46 and the engagement of the upturned member 56 with the dog 53 and the consequent movement of the bar 57 in a lengthwise direction, the shipper 49 is pulled 60 from its notch and is thereby moved by its spring in the usual manner so as to move the shipper rod 50 in the direction of the arrow in Fig. 15. The shipper rod in making this movement not only shifts the belt from the 65 fast to the loose pulley, but it passes under

and slightly elevates a wire 67 shown as having bent upper and lower ends and loosely mounted in the extension 63, so that when lifted it lifts the extension 64, owing to the loose mounting of the parts, thus releasing 70 its hooked end 65 from the end 66 on the said extension 63. This at once releases the armature from the position in which it is held against the magnet and it is at once returned by its spring 68 into the non-active 75 position shown in Fig. 14, all parts being thus restored to non-active position. Thus upon the lifting of the stop bar 22 the circuit is closed and the armature 46 energized 80 so as to stop the loom and the stopping movement of the shipper rod at once returns the armature to its inactive position, but not until the upturned end 56 of the rod 57 has been engaged by the dog 53 to effect the release of the shipper. 85

Any other suitable means whether electrical or mechanical may be provided to operate the shipper mechanism,—that is, the loom-stopping mechanism proper,—upon the occurrence of warp fault and the described 90 movement of the double heddle device shown in Figs. 9, 10 and 11, and I desire it to be understood that my invention is in no wise restricted to the particular operating means described. Preferably, however, I employ 95 a stop bar, rod or tube such as indicated at 22 and which is adapted to be lifted upon the occurrence of warp fault,—that is, either warp breakage or undue slackness, of any of the warp ends. 100

It will be understood from the foregoing description that the warp stop device is positive in its action and is not dependent upon the action of gravity. By avoiding the use of warp drops I do away with the 105 necessity for drawing the warp ends through drop devices in addition to the heddles and in the preferred embodiment of my invention I am enabled to utilize the so-called “cotton harnesses” which do not chafe or 110 fray the warp ends.

So far as I am aware, I am the first to provide a warp stop motion for looms responsive to warp fault, and wherein a distinct indicating element is not provided for 115 each warp thread or pair of warp threads.

Having thus described one illustrative embodiment of my invention, I desire it to be understood that although specific terms are employed, they are used in a generic and descriptive sense and not for purposes of limitation, the scope of the invention being set forth in the following claims. 120

Claims—

1. Loom stopping mechanism comprising 125 in combination, a heddle frame having upper and lower cross members, a series of double heddle devices of loop form supported upon said cross members for movement thereabout, a member exterior to said 130

- frame and adapted to be moved by that one of said heddle devices pertaining to a faulty warp end, shipper mechanism and connections from said member thereto.
5. Loom stopping mechanism comprising in combination, a heddle frame having upper and lower cross members, a series of double heddle devices of loop form supported upon said cross members for movement thereabout, a member exterior to said frame and normally at rest during the operation of the loom, but adapted to be moved by that one of said heddle devices pertaining to a faulty warp end, shipper mechanism and connections from said member thereto.
10. Loom stopping mechanism comprising in combination, a heddle frame having upper and lower cross members, a series of double heddle devices of loop form supported upon said cross members for movement thereabout, a transverse bar, extensions from said heddle devices to embrace said bar, thereby to move the latter in the event of thread fault, an electric circuit closed by the moving of said bar, and shipper mechanism operatively actuated by the closing of said circuit.
15. Loom stopping mechanism comprising in combination, a heddle frame having upper and lower cross members, a series of double heddle devices of loop form supported upon said cross members for movement thereabout, a stop device, extensions from said heddle devices to said stop device, thereby 20 to move the latter in the event of thread fault, shipper mechanism and connections from said shipper mechanism to said stop device.
25. Loom stopping mechanism comprising in combination a heddle frame having upper and lower cross members, a series of double heddle devices of loop form supported upon said cross members for movement thereabout, a stop device, extensions from said heddle devices to said stop device, thereby 30 to move the latter in the event of thread fault, shipper mechanism and connections from said shipper mechanism to said stop device.
35. Loom stopping mechanism comprising in combination, a heddle frame having upper and lower cross members, a series of double heddle devices of loop form supported upon said cross members for movement thereabout, a stop member, extensions from each of said devices to engage said stop member, and to displace the same in the event of warp fault, and shipper mechanism 40 operatively connected to said member.
45. Loom stopping mechanism comprising in combination, a heddle frame having upper and lower cross members, a series of double heddle devices supported upon said cross members and each having movement thereon to effect the lifting of one of the parts thereof upon the lowering of the companion part consequent upon fault in the warp end of said elevated part, shipper mechanism, a stop device movable with the heddle frame but spaced from the cross members thereof, 50 said stop device being connected to the heddle devices to be displaced thereby in the event of warp fault, and operative connections between said stop device and said shipper mechanism.
55. Loom stopping mechanism comprising in combination, heddle frames having means to effect the shedding operation, flexible guiding means for said heddle frames, and with respect to which the heddle frames have up and down shedding movement, stop heddles supported by said frames, and shipper mechanism having operative connection to said stop heddles.
60. Loom stopping mechanism comprising in combination a heddle frame having means to impart a shedding movement thereto, flexible guiding means for said heddle frame and with respect to which said frame is reciprocable in the shedding operation, said guiding means having a suitable support, stop heddles supported by said frame and shipper mechanism having operative connection to said heddles.
65. Loom stopping mechanism comprising in combination a heddle frame having means to impart a shedding movement thereto, flexible guiding means for said heddle frame and with respect to which said frame is reciprocable in the shedding operation, said guiding means having a suitable support, stop heddles supported by said frame and shipper mechanism having operative connection to said heddles.
70. Loom stopping mechanism comprising in combination a heddle frame having means to impart a shedding movement thereto, flexible guiding means for said heddle frame and with respect to which said frame is reciprocable in the shedding operation, said guiding means having a suitable support, stop heddles supported by said frame and shipper mechanism having operative connection to said heddles.
75. Loom stopping mechanism comprising in combination a heddle frame having means to impart a shedding movement thereto, flexible guiding means for said heddle frame and with respect to which said frame is reciprocable in the shedding operation, said guiding means having a suitable support, stop heddles supported by said frame and shipper mechanism having operative connection to said heddles.
80. Loom stopping mechanism comprising in combination a heddle frame having means to impart a shedding movement thereto, flexible guiding means for said heddle frame and with respect to which said frame is reciprocable in the shedding operation, said guiding means having a suitable support, stop heddles supported by said frame and shipper mechanism having operative connection to said heddles.
85. Loom stopping mechanism comprising in combination a heddle frame having shed forming means connected thereto, flexible guides for said frame permitting movement of the latter toward and from the front and rear of the loom, and with respect to which guides the heddle frame is reciprocable in the shedding movement, shipper mechanism, and means supported by said guiding means and operatively connected to said shipper mechanism to effect loom stoppage in the event of warp fault.
90. Loom stopping mechanism comprising in combination a heddle frame having shed-forming means connected thereto, stop heddles supported by said heddle frames, flexible guides for said frames permitting movement of the latter toward and from the front and rear of the loom, and with respect to which guides the heddle frame is reciprocable in the shedding movement, shipper mechanism, and means supported by said guiding means and operatively connected to said shipper mechanism to effect loom stoppage in the event of warp fault.
95. Loom stopping mechanism comprising in combination a heddle frame having shed-forming means connected thereto, stop heddles supported by said heddle frames, flexible guides for said frames permitting movement of the latter toward and from the front and rear of the loom, and with respect to which guides the heddle frame is reciprocable in the shedding movement, shipper mechanism, and means supported by said guiding means and operatively connected to said shipper mechanism to effect loom stoppage in the event of warp fault.
100. Loom stopping mechanism comprising in combination, a heddle frame having shed-forming means connected thereto, stop heddles supported by said heddle frames, flexible guides for said frames permitting movement of the latter toward and from the front and rear of the loom, and with respect to which guides the heddle frame is reciprocable in the shedding movement, shipper mechanism, and means supported by said guiding means and operatively connected to said shipper mechanism to effect loom stoppage in the event of warp fault.
105. Loom stopping mechanism comprising in combination, a heddle frame, flexible guiding strips therefor between the side frames of the loom, stop heddles supported by said frame, and a cross bar supported by said flexible guiding strips and operatively connected to said stop heddles to be moved thereby in the event of warp fault.
110. Loom stopping mechanism comprising in combination, a heddle frame, flexible guiding strips therefor between the side frames of the loom, stop heddles supported by said frame, and a cross bar supported by said flexible guiding strips and operatively connected to said stop heddles to be moved thereby in the event of warp fault.
115. Loom stopping mechanism having a heddle frame, flexible guiding strips therefor, and with respect to which strips said heddle frame is reciprocable in the shedding movement, a device mounted in said flexible guiding strips, means actuated upon thread fault to move said device, and shipper mechanism operatively connected to said device.
120. Loom stopping mechanism having a heddle frame, flexible guiding strips therefor, and with respect to which strips said heddle frame is reciprocable in the shedding movement, a device mounted in said flexible guiding strips, means actuated upon thread fault to move said device, and shipper mechanism operatively connected to said device.
125. Loom stopping mechanism having a heddle frame, flexible guiding strips therefor, and with respect to which strips said heddle frame is reciprocable in the shedding movement, a stop device adjacent said heddle frame, means actuated upon thread fault to

move said stop device, and shipper mechanism operatively connected to said stop device.

14. Loom stopping mechanism comprising in combination, a stop device and supporting holders therefor, heddle frame guiding members, means to connect said holders to said heddle frame guiding members with capacity for adjustment of said holders and 10 shipper mechanism operatively connected to said device.

15. Loom stopping mechanism comprising a heddle frame, a set of heddles supported thereby, and a stop member co-acting with 15 said heddles, each of said heddles having upper and lower two stranded portions, a single stranded eye, and a single stranded loop extending below said frame and engaging said stop member.

20 16. In a stopping mechanism for looms, the following instrumentalities:—a shipping device, a continuous nonmetallic duplex heddle having warp end receiving formation composed of the same substance, a frame 25 having two cross pieces on which said duplex heddle is slidably mounted, and intermediate connections between said shipping device and said duplex heddle, to actuate the former upon sliding movement of the latter.

30 17. In a stopping mechanism for looms, the following instrumentalities:—a shipping device, a continuous nonmetallic duplex heddle, a frame having two cross pieces on 35 which said duplex heddle is slidably mounted, and intermediate connections between said shipping device and said duplex heddle to actuate the former upon sliding movement of the latter.

18. Loom stopping mechanism comprising 40 in combination a heddle frame having upper and lower cross members, a series of double heddle devices of loop form supported upon said cross members for movement thereabout, a stop member adjacent to said heddle 45 frame, extensions from each of said devices to engage said stop member and to displace the same in the event of warp fault, and shipper mechanism operatively connected to said member.

50 19. Loom stopping mechanism comprising a heddle frame, a set of heddles supported thereby and a stop device co-acting with 55 said heddles, each of said heddles having upper and lower two stranded portions, a single stranded eye, and a single stranded loop engaging said stop device.

20. Loom stopping mechanism comprising in combination a heddle frame having upper and lower cross members, a series of duplex 60 heddle devices supported upon said cross members, shipper mechanism, and a single member adjacent but exterior to said heddle frame and also adjacent to said duplex heddles and with which single member the latter 65 coöperate to stop the loom.

21. Loom stopping mechanism comprising in combination, a double heddle device consisting of a strand arranged in loop form providing supporting portions at the upper and lower bends of said loop, and having 70 means to receive a pair of warp ends, shipper mechanism and operative connections between said heddle device and said shipper mechanism.

22. Loom stopping mechanism comprising 75 in combination, a double heddle device consisting of a strand arranged in loop form providing supporting portions at the upper and lower bends of said loop, and having 80 means having formations to receive two warp threads, shipper mechanism, and means responsive to fault in either warp thread to operate said shipper mechanism to stop the loom.

23. Loom stopping mechanism comprising 85 in combination, a heddle frame having upper and lower cross members, a series of double heddle devices of loop form supported upon said cross members for movement thereabout, shipper mechanism, and 90 operative connections between said shipper mechanism and each of said heddle devices to operate the shipper mechanism in the event of thread fault.

24. Loom stopping mechanism comprising 95 in combination, a heddle frame having upper and lower cross members, a series of double heddle devices of loop form supported upon said cross members for movement thereabout, shipper mechanism, and 100 electrically operated connections between said heddle devices and the shipper mechanism to stop the loom in the event of warp breakage.

25. Loom stopping mechanism comprising 105 in combination, a heddle frame having upper and lower cross members, a series of double heddle devices of loop form supported upon said cross members for movement thereabout, a member adapted to be 110 lifted by that one of said heddle devices pertaining to a faulty warp end, shipper mechanism and connections from said member thereto.

26. Loom stopping mechanism comprising 115 in combination, a heddle frame having upper and lower cross members, a series of double heddle devices of loop form supported upon said cross members for movement thereabout, a bar adapted to be lifted 120 by that one of said heddle devices pertaining to a broken warp end, shipper mechanism, and connections between the same and said bar.

27. Loom stopping mechanism comprising 125 in combination, a heddle frame having upper and lower cross members, a series of double heddle devices of loop form supported upon said cross members for movement thereabout, a bar adapted to be lifted by 130

that one of said heddle devices pertaining to a faulty warp end, an electric circuit adapted to be closed by the lifting of the said bar, and shipper mechanism operatively connected to said circuit.

28. Loom stopping mechanism comprising in combination, a heddle frame having upper and lower cross members, a series of double heddle devices of loop form supported upon said cross members for movement thereabout, a transverse bar, extensions from said heddle devices to embrace said bar, thereby to lift the latter in the event of thread fault, an electric circuit closed by the lifting of said bar, and shipper mechanism operatively actuated by the closing of said circuit.

29. Loom stopping mechanism comprising in combination, a heddle frame having upper and lower cross members, a series of double heddle devices of loop form supported upon said cross members for movement thereabout, each of said heddle devices having a looped, lower extension, a bar positioned in said looped extensions to be displaced by movement of a heddle device about said cross members, and shipper mechanism actuated upon displacement of said bar.

30. Loom stopping mechanism comprising in combination, a heddle frame having upper and lower cross members, a series of double heddle devices of loop form supported upon said cross members for movement thereabout, a cross bar, extensions from each of said devices to engage said cross bar and to displace the same in the event of warp fault, and shipper mechanism operatively connected to said bar.

31. Loom stopping mechanism comprising in combination, a heddle frame having upper and lower cross members, a series of double heddle devices of loop form supported upon said cross members for movement thereabout, a cross bar, extensions from each of said devices to engage said cross bar and to displace the same in the event of warp fault, an electric circuit adapted to be affected by the displacement of said bar, and shipper mechanism adapted to be operated upon change in said electric circuit.

32. Loom stopping mechanism comprising in combination, a heddle frame having upper and lower cross members, a series of double heddle devices of loop form supported upon said cross members for movement thereabout, each member of each double heddle device having a warp end receiving eye, shipper mechanism, and operative connections to the shipper mechanism rendered active upon the lifting of that member of a double heddle device having a faulty warp end.

33. Loom stopping mechanism comprising in combination, a heddle frame having upper and lower cross members, a series of

double heddle devices of loop form supported upon said cross members for movement thereabout, each member of each double heddle device having a warp end receiving eye, shipper mechanism and operative connections to the shipper mechanism rendered active upon the lifting of that member of a double heddle device having a faulty warp end, and to depress the companion member of said double heddle device through the action of its unbroken warp end.

34. Loom stopping mechanism comprising in combination, a heddle frame having upper and lower cross members, a series of double heddle devices supported upon said cross members and having movement thereon to effect the lifting of one of said members upon the lowering of the companion member consequent upon fault in the warp end of said elevated member, shipper mechanism, a bar extending transversely of the loom and connected to said heddle devices to be lifted upon the event of warp fault, and operative connections between said bar and said shipper mechanism.

35. Loom stopping mechanism comprising in combination, a heddle frame, guiding means therefor between the side frames of the loom and independent thereof, and with respect to which said frame is reciprocable in the shedding movement, heddles supported by said frame, shipper mechanism, and operative connections between said heddles and shipper mechanism to stop the loom in the event of warp fault.

36. Loom stopping mechanism comprising in combination, a heddle frame, guiding means therefor between and independent of the side frames of the loom and extending upwardly from the floor, and with respect to which said frame is reciprocable in the shedding movement, stop heddles supported by said heddle frame, and shipper mechanism actuated from said stop heddles in the event of warp fault.

37. Loom stopping mechanism comprising heddle frames having means to effect the shedding operation, flexible guiding means for said heddle frame extending upward from the floor, and with respect to which said frames are reciprocable in the shedding movement, stop heddles supported by said frame, and shipper mechanism having operative connections to said stop heddles.

38. Loom stopping mechanism comprising in combination, a heddle frame having shed forming means connected thereto, flexible guides for said frame permitting movement of the latter toward and from either side frame of the loom and toward the front and rear of the loom, and with respect to which said frame is reciprocable in the shedding movement, shipper mechanism, and means supported by said guiding means and operatively connected to said shipper mechanism

to effect loom stoppage in the event of warp fault.

39. Loom stopping mechanism comprising in combination, a heddle frame, flexible guiding strips therefor extending upward from the floor between the side frames of the loom, stop heddles supported by said frame, and a cross bar supported by said flexible guiding strips and operatively connected to said stop heddles to be moved thereby in the event of warp fault.

40. Loom stopping mechanism having a heddle frame, flexible guiding strips therefor, a stop bar mounted in said flexible guiding strips, means actuated upon thread fault to move said stop bar, and shipper mechanism operatively connected to the stop bar.

41. Loom stopping mechanism comprising a stop bar and supporting holders therefor, heddle guiding members, means to connect said holders to said heddle guiding members with capacity for adjustment of said holders, and shipper mechanism operatively connected to said bar.

42. Loom stopping mechanism comprising a stop bar arranged transversely of the loom, supporting boxes receiving the ends of said bar, a heddle, upright guiding strips therefor between and distinct from the side frames of the loom, means to connect said boxes and strips with capacity for vertical adjustment of the boxes, and stop devices operatively connected to said bar.

43. Loom stopping mechanism comprising a stop bar arranged transversely of the loom, supporting boxes receiving the ends of said bar, a heddle frame, upright guiding strips therefor between and distinct from the side frames of the loom, means to connect said boxes and strips with capacity for vertical adjustment of the boxes, stop devices carried by said heddle frame and operatively connected to said bar to displace the same in the event of warp fault, an electric circuit including said bar, and shipper mechanism under the control of said electric circuit.

44. Loom stopping mechanism having a bar adapted to be displaced in the event of warp fault, end supporting boxes therefor, an electric circuit connected to said boxes, a heddle frame, guides therefor, means adjustably to connect said boxes to said guides, a shipper, and operative connections between the bar and shipper.

45. Loom stopping mechanism comprising a shipper with means to hold the same in loom operating position, an electric circuit having an armature adapted to be energized upon thread fault, a lay having a projection, a member having means operatively to engage the shipper and moved by said armature into the path of movement of said projection, said member having a holding extension and a fixed part with which

said holding extension engages, to hold said member in the path of the projection until engaged thereby.

46. Loom stopping mechanism comprising a shipper with means to hold the same in loom operating position, an electric circuit having an armature adapted to be energized upon thread fault, a lay having a projection, a member having means operatively to engage the shipper and moved by said armature into the path of movement of said projection, said member having a holding extension and a fixed part with which said holding extension engages to hold said member in the path of the projection until engaged thereby, and means to release said holding member upon stopping movement of the shipper.

47. In a loom, a set of heddle frames, a set of heddles hung upon a cross member thereof, each heddle being formed of a flexible, twisted texture in loop form, and movable about said cross member, said heddle having eyes formed from said material and permitting the passage therethrough of a warp end, said heddles being coated with sizing to prevent elongation, and means co-acting with said heddles to effect the stoppage of the loom upon the breakage of a warp end.

48. Loom stopping mechanism comprising in combination, a heddle frame having upper and lower cross members, a series of double heddle devices consisting of strands in loop form, portions of said strands being received upon said cross members for movement thereabout, a stop member adapted to be moved by that one of said heddle devices pertaining to a faulty warp end, shipper mechanism, and connections from said stop member thereto.

49. In a loom, a set of heddle frames, heddles hung to the top and bottom cross members of said frames, said heddles being formed of flexible twine in loop form and movable about said cross members, said heddles having elongated eyes for the warp ends, in combination with means co-acting with said heddles to stop the loom upon the undue slackening or breakage of any of the warp ends.

50. Loom stopping mechanism including a heddle in loop form for support upon and movement about cross members of the heddle frame, said heddle having a pair of varnished, elongated eyes for the passage of warp ends, and means co-operating with said heddle to stop the loom upon the occurrence of fault in an end passing through either of said eyes.

51. Loom stopping mechanism comprising in combination, shipper mechanism, a heddle frame, having cross members, a heddle of loop form mounted upon and movable about said cross members, said heddle having a pair of eyes for the reception of warp

ends, said eyes being formed of a soft texture, two strands of the heddle leading from the lower cross member of the heddle frame and two strands leading from the upper 5 cross member thereof and uniting to form a knotless eye substantially in the center of said frame, and operative connections between said heddle and the shipper mechanism to stop the loom when the eye is released by the undue slackening or breaking 10 of a warp end.

52. Loom stopping mechanism including a heddle frame, having upper and lower cross members, a heddle composed of a strand of 15 loop form, mounted upon and movable about said cross members, said heddle having an eye separated from the body of the heddle by two half knots, and means co-acting with said heddle to stop the loom in the event of 20 warp fault.

53. In a loom, a heddle frame, a heddle device mounted therein to operate a plurality of warp ends, a member exterior to said heddle frame, shipper mechanism, operative 25 connections between said member and said shipper mechanism and connections between said member and said heddle device and positively operated by the heddle device in the event of warp fault, to stop the loom through 30 the instrumentality of said shipper mechanism.

54. In a loom, a heddle frame, a heddle device mounted therein to operate a plurality of warp ends, a member exterior to said 35 heddle frame, shipper mechanism, operative connections between said member and said shipper mechanism, and connections between said member and said heddle device and operated by positive lifting movement 40 of a portion of said heddle device, in the event of warp fault, to stop the loom through the instrumentality of said shipper mechanism.

55. In a loom, a heddle frame, a duplex 45 heddle device mounted therein and having two members each adapted to receive a warp end, a stopping instrumentality exterior to said heddle frame and a flexible connection between said instrumentality and said heddle device, and operated by the latter through the instrumentality of an unbroken warp, in the event of fault in the companion warp.

56. In a loom stopping mechanism, a heddle 55 frame, a pair of flexible uprights therefor and with respect to which said heddle frame is reciprocable in the shedding movement, guides holding said uprights in position, and means for attaching said guides 60 and heddles.

57. Loom stopping mechanism comprising 65 a heddle frame, a set of heddles supported thereby, and a stop rod co-acting with said heddles, each of said heddles having upper and lower, two-stranded portions, a single

stranded eye and a single stranded loop extending below said frame and about said rod.

58. In a loop stopping mechanism, a heddle frame, a set of heddles having eyes for the reception of warp ends, and mounted 70 upon said heddle frame in two series, corresponding members of said heddles being connected for movement in opposite directions, a movable member adjacent to said heddles and with which the latter conjointly 75 coöperate, said member being exterior to the heddle frame but having movement with the heddle frame and shipper mechanism operatively connected to said member and actuated by movement of the latter. 80

59. In a loom stopping mechanism, a set of duplex heddles having eyes for the reception of a series of warp ends, a heddle frame wherein said heddles are mounted, a movable member adjacent to said duplex 85 heddles and with which the latter conjointly coöperate, provisions for preventing relative movement of said heddle frame and member during the normal operation of the loom and shipper mechanism operatively 90 connected to said member and actuated by movement of the latter.

60. In a loom stopping mechanism, a duplex heddle having eyes for the reception of warp ends and of non-metallic material 95 throughout, the members of said heddle being simultaneously movable in opposite directions, a member adjacent to said heddle and with which the latter coöperates, and shipper mechanism operatively connected to 100 said member, to stop the loom.

61. In a loom stopping mechanism, a heddle composed throughout of non-metallic material looped to form a heddle body and eye, shedding connections to operate said 105 heddle in a vertical plane, a secondary member normally at rest, connecting means between said heddle and member to actuate the latter in the event of warp fault and shipper mechanism to which said member is operatively connected. 110

62. In a loom stopping mechanism, a non-metallic, one-substance heddle having an opening for the reception of a single warp end, a heddle frame whereon said heddle is mounted, means for imparting upward movement to said heddle upon release by said warp end, a secondary device exterior to said heddle frame and mechanically operated upon by said heddle in the event of 115 warp fault, shedding mechanism supporting said heddle and means to stop the operation of said mechanism in the event of fault in said warp end. 120

63. In a stopping mechanism for looms, a set of duplex heddles of loop form and having knotless openings for the reception of warp ends, said heddles being composed throughout of textile material, a single secondary device operatively connected to said 125 130

5 heddles and actuated by upward movement of a heddle opening pertaining to a faulty warp end, shedding mechanism supporting said heddles and coöperating means to stop said shedding mechanism upon warp fault pertaining to said heddles.

10 64. In a stopping mechanism for looms, a set of duplex heddles of loop form and having knotless openings for the reception of warp ends, said heddles being composed throughout of textile material, a single secondary device consisting of a hollow rod having indicating ends, said rod being operatively connected to said heddles, and actuated by upward movement of a heddle opening pertaining to a faulty warp end, shedding mechanism supporting said heddles, and coöperating means to stop said shedding mechanism upon warp fault pertaining to said heddles.

15 65. Loom stopping mechanism comprising a shipper with means to hold the same in loom operating position, an electric circuit having an armature adapted to be energized upon thread fault, a lay having a projection, a member carried by the armature and moved thereby into the path of said projection, and having means operatively to engage the shipper, said member having holding means with which said holding means coöperates to effect the holding of said member in the path of said projection.

20 66. Loom stopping mechanism comprising in combination, a heddle frame having upper and lower cross members, a series of double heddle devices supported upon said cross members and each having movement thereon to effect the lifting of one of the parts thereof upon the lowering of the companion part consequent upon fault in the warp end of said elevated part, shipper mechanism, a hollow rod connected to said heddle devices to be displaced upon the event of warp fault, and operative connections between said rod and said shipper mechanism.

25 67. Loom stopping mechanism comprising in combination, a heddle frame having upper and lower cross members, a series of double heddle devices of loop form supported upon said cross members for movement thereabout, a hollow rod exterior to said frame and adapted to be moved by that one of said heddle devices pertaining to a faulty warp end, shipper mechanism and connections from said rod thereto.

30 68. Loom stopping mechanism comprising in combination, a heddle frame having upper and lower cross members, a series of double heddle devices of loop form supported upon said cross members for movement thereabout, means for flexibly guiding said heddle frame for movement in a vertical plane, a stop member exterior to said frame and supported by said flexible guiding

means, and adapted to be moved by that one of said heddle devices pertaining to a faulty warp end, shipper mechanism and connections from said member thereto.

35 69. Loom stopping mechanism comprising in combination, a heddle frame having upper and lower cross members, heddles collapsible in the direction of their length, supported upon said cross members, means for flexibly guiding said heddle frame for movement in a vertical plane, a stop member exterior to said frame and supported by said flexible guiding means, and adapted to be moved by that one of said heddle devices pertaining to a faulty warp end, shipper mechanism, and connections from said member thereto.

40 70. A loom stopping mechanism comprising a heddle frame having cross members, heddles mounted thereon for shifting movement and having eyes for the reception of warp ends, said eyes making a shifting in position when released by either warp end, a stop device and flexible means passing freely about said device to displace the latter when said eyes shift into stopping position.

45 71. In a loom, a shedding mechanism, a heddle frame having a series of heddles formed with eyes for the reception of warp ends and mounted in said heddle frame to shift vertically when released by said warp ends, connections between said shedding mechanism and said heddle frames to operate the latter to form successive sheds, combined with shipper mechanism and a stop device having flexible connections with said heddles and moved thereby to operate to stop said shedding mechanism through the instrumentality of said stop device.

50 72. In a loom, a series of heddles having openings for the reception of warp ends and adapted to be shifted into upper and lower positions, a harness frame in which said heddles are mounted for such shifting movement, and means to shift said frame, a device exterior of said frame forming part of a stopping mechanism operatively connected to said heddles, the latter when released by a faulty warp end actuating the former to stop the shifting of said harness frame.

55 73. In a loom, a shedding mechanism, a heddle frame having a series of heddles formed with eyes for the reception of warp ends and mounted in the heddle frame to shift vertically when released by said warp ends, connections between said shedding mechanism and said heddle frames to operate the latter to form successive sheds, combined with shipper mechanism and a stop device exterior to said heddle frame, said device having a flexible connection with said heddles, and positively moved thereby upon warp fault to stop said shedding mechanism.

60 74. In a loom, a heddle frame, a duplex heddle device mounted therein and having

two members each adapted to receive a warp end, a stopping instrumentality, and a flexible direct connection between said instrumentality and said heddle device operated by the latter through the instrumentality of an unbroken warp, in the event of fault in the companion warp.

75. In a loom, a heddle frame, a plurality of duplex heddle devices mounted therein, 10 each of said heddle devices having two members, each of which members is adapted to receive a warp end, a stopping instrumentality exterior to said heddle frame, and a separate flexible connection from each heddle device to said stopping instrumentality and operated by the former through the instrumentality of an unbroken warp in the event of fault in the companion warp.

76. In a loom, a heddle frame, a plurality 20 of duplex heddle devices mounted therein, each of said heddle devices having two members, each of which members is adapted to receive a warp end, a stopping instrumentality and a separate flexible connection 25 from each heddle device to said stopping instrumentality and operated by the former through the instrumentality of an unbroken warp, in the event of fault in the companion warp.

77. In a loom, a heddle frame, a duplex heddle mounted thereon and having two members, each adapted to receive a warp end, a stopping instrumentality exterior to 35 said heddle frame, an extension from said heddle to said instrumentality and means for imparting positive movement to said extension and thereby to operate said instrumentality in the event of warp fault.

78. In a loom, a heddle frame, a duplex 40 heddle mounted therein and having two members each adapted to receive a warp end, a stopping instrumentality exterior to said heddle frame, an extension from said heddle to said instrumentality, said extension being directly connected both to the 45 heddle and to said stopping instrumentality, and means for imparting positive movement to said extension and thereby to operate said instrumentality in the event of 50 warp fault.

79. In a loom, a heddle frame having a shedding connection, a duplex heddle mounted in said frame and having two members each adapted to receive a warp 55 end, a stopping instrumentality exterior to

said frame, and an operating connection between said duplex heddle and said instrumentality that permits the heddle frame to rise and fall in the shedding operation without operation of said instrumentality except 60 upon the occurrence of warp fault in one of said ends.

80. In a loom, a heddle frame, a heddle mounted therein, a stopping instrumentality exterior to said frame, and a direct flexible 65 connection between said heddle and said stopping instrumentality and acting to operate said instrumentality through the tension of an unbroken warp in the event of warp fault in the opposite plane of the 70 shed.

81. In a loom, a heddle frame, a duplex heddle mounted therein and having two members each adapted to receive a warp end, a stopping instrumentality exterior to 75 said heddle frame, a flexible looped extension from said heddle to and about said instrumentality and means for imparting positive movement to said extension and thereby to operate said instrumentality in the 80 event of warp fault.

82. Loom stopping mechanism comprising a shipper, means to hold the same in loom-operating position, a lay having a loom-stopping projection, a member adapted to be 85 moved into the path of said projection in the event of warp fault, a device 57 to engage the shipper and operatively connected to said member, and means having a lost motion connection directly with said device 90 for controlling the movement of said member.

83. Loom stopping mechanism comprising a shipper, means to hold the same in loom-operating position, a lay having a 95 loom-stopping projection, a member adapted to be moved into the path of said projection in the event of warp fault, a device to engage the shipper and operatively connected to said member, and an armature 100 having a limited sliding connection along with said device for controlling the movement of said member.

In testimony whereof, I have signed my name to this specification, in the presence 105 of two subscribing witnesses.

RANDOLPH CROMPTON.
